Stewart E. Seaman

UNITED STATES PATENT OFFICE

1,996,002

DECREASING INFLAMMABILITY OF
CIGARETTES

Stewart Elmer Seaman, White Plains, N. Y.

Application May 25, 1933, Serial No. 672,837

16 Claims. (Cl. 131—52)

My invention relates to the preparation of a cigarette of decreased inflammability at a given point or points in or on said cigarette, by the attachment to the inside or outside of the wrap-
5 per for the tobacco portion, or by the treatment of the paper at a predetermined place or places, with a solution, compound or product of non-cellulosic nature which retards or diminishes inflammability at the point or places treated, so
10 that when said cigarette is normally smoked or reduced in length by burning to the point or points in contact with the fire-retardant, the tendency to continuation of burning, is mate-
15 rially lessened. My invention, therefore, com-
prehends a treatment of the paper portion or
20 wrapper of a cigarette in any manner which will
materially diminish its inflammability and speed
of burning where the treated paper wrapper comes
in contact with the burning cigarette, thereby
25 materially lessening the fire hazard when such
partially consumed cigarette is discarded while
still burning—as usually is the case.

By my treatment of the paper portion of a cigarette, when the same is normally smoked to the
25 point or place of treatment—or treatments if the
inflammability-reducing treatment has been ap-
plied to more than one portion of the paper
wrapper of the cigarette—when the unsmoked
30 portion is discarded, said unsmoked portion will
be almost immediately extinguished automatic-
ally, instead of being left perhaps in contact
with inflammable material where ignition may
take place, and a conflagration thereby initiated.
35 Usually when a partially smoked cigarette is dis-
carded, the smoker seldom remains watching the
same until it is extinguished.

One object of my invention is to produce a
40 paper wrapper which has been treated at a pre-
determined place and for a predetermined
width—usually from one-fourth to three-fourths
of an inch depending upon the avidity of fire-
retardant possessed by the paper so treated—
45 which will immediately diminish the inflammability
and curtail the burning power of tobacco
inside said wrapper, whether the remains of the
cigarette be held in the mouth of the smoker or
discarded.

Another object is to treat the cigarette wrapper
50 with the fire-reducing material at the place on
the cigarette where experience has shown that
it is normally discarded, which is when the nor-
mal length of the cigarette has been reduced by
from one-fourth to three-fourths, and in general
55 to about one-half the original length.

It is essential in this treatment of cigarette

paper, that the material used for the purpose of
diminishing inflammability be colorless or nearly
so unless it is preferred to directly add a coloring
matter to produce a distinctive appearance;
should be tasteless, substantially odorless, not
materially increase the smoke normally given
off in the smoking operation, and leave no peculiar
taste in the mouth after smoking, that can prop-
erly be ascribed to the presence of the fire-retard-
ant in the paper wrapper.

Statistics of fire insurance companies give tan-
gible evidence of the large losses sustained by
fires initiated by the careless discarding of par-
tially smoked and still burning cigarettes in con-
tact with inflammable material.

My invention in its broad sense comprehends
reducing the inflammability of a cigarette at any
point or place where the paper wrapper thereof
has been treated with an inflammability-reduc-
ing material answering the specifications above
20 mentioned, whether said addition to the wrap-
per be in the dissolved or undissolved condition,
whether it be a solid or a liquid, and if a liquid,
irrespective as to whether said liquid is aqueous,
25 non-aqueous or both, as a compound solvent, or
whether the material is applied directly to the
paper either before or after the paper has been
wrapped around the tobacco, or whether the in-
flammability-reducing material is first applied to
30 a paper or other cellulosic or non-cellulosic base,
and then attached to the side of the paper ex-
terior to or in contact with the tobacco.

As suitable products for the purposes of this
invention, have been found aqueous solutions
35 of inorganic salts or other chemical compounds,
such as ammonium sulfate, chloride, sulfate or
phosphate or boric acid or sodium salts of the
same. Sodium silicate or other alkali metal sili-
cate are other examples of water-soluble fire-
40 retardants suitable for the carrying out of this
invention. Of the water-insoluble salts suitable
may be mentioned alkali earth metal sulfates,
carbonates, sulfates, phosphates and oxalates.
Of materials soluble in volatile solvents, there is
45 included the cellulose organic esters and cellulose
ethers, natural resins, oleo-resins and resinous
bodies; so-called synthetic resins and phenol-
aldehyde condensate bodies or other condensates
used in connection with or in the preparation of
synthetic resins and resinous bodies. Bakelites
50 and glyptals are examples of such bodies. Case-
in-aldehyde or other casein or nitrogenous-con-
taining suitable bodies fall within the scope of
this invention where their properties meet the
specifications as above outlined.

As one example of carrying my invention into effect, and given for illustrative purposes only, I may dissolve 12 ounces of cellulose acetate in 2 quarts of a mixture of 65% acetone by weight and 35% ethyl acetate by weight, to which has been added 5 ounces synthetic resin and 12 ounces calcium sulfate, the latter being stirred into the otherwise completed formula. A sufficient amount of this lacquer or mixture is placed by brushing or otherwise on a cigarette paper of the normal size used in cigarette manufacture, on said paper in a band of about one-fourth to three-fourths inches wide, either as a single coating or a plurality of coatings either on the side of the paper which normally will be next to the tobacco, or on the other side, or on both sides, and the paper allowed to dry by solvent evaporation either at normal or elevated temperatures.

Or, the fire-retarding composition may be placed on the paper in any approved manner while the paper is in large sheet or in roll form by any suitable mechanical device or manually.

In the illustrative example above, the cellulose ester may be entirely replaced by a resinous material, a phenol-aldehyde condensate, a casein compound or other fire-retardants. If a water-soluble composition is employed, such as an aqueous solution of inorganic salts, a saturated solution is preferably prepared and applied to the portion of the paper desired of width required in order to induce the degree of fire-retarding effect required.

Normally it has been found that the use of a single band of fire retardant composition is sufficient, or a single application of a non-cellulosic inflammability-reducing composition, and experience has shown that, inasmuch as a cigarette is normally discarded when between three-fourths and one-fourth smoked,—usually when about a half or a little less—that the fire-retarding composition should be placed at that distance from the end of the cigarette normally lighted.

It is not intended that the fire-proofing composition shall be placed on or in the cigarette paper wrapper sufficiently near the end normally placed in the mouth so as to touch the lips of the smoker, or elsewhere so as to materially interfere with the normal smoking of the cigarette. A cigarette made according to my invention will go out when held between the lips and when smoked to the point of application of the fire-retardant, unless drawn upon vigorously and continuously, and until the cigarette has been consumed beyond this point.

In the accompanying drawing, Fig. 1 represents a cigarette, the fire-retardant band being indicated at "A". In Fig. 2 is shown the paper before wrapping around tobacco, the fire retardant portion being indicated as at A¹, A² and A³.

I am aware of U. S. Patent 931,629 for "Impregnating or coating the ends of cigars" so the same will not touch the lips of the smoker; U. S. Patent 779,687 for a "Mouthpiece for a cigarette or cigar"; and German Patent 378,122 to encase the entire length of a cigarette in a transparent cellulose-containing wrapper as of cellophane. I disclaim all features embodied in said issued patents.

70 What I claim is:—

1. A process for reducing the inflammability of that portion of a cigarette which normally is discarded, comprising coating the paper portion of the cigarette for the width desired with a resinous composition, as herein set forth.

2. A process for reducing the inflammability of that portion of a cigarette which normally is discarded, comprising impregnating the paper wrapper by an inflammable solution of a non-cellulosic composition containing an inflammability-reducing material therein, as herein set forth. 5

3. A process for reducing the inflammability of a cigarette at a pre-determined place, comprising coating the wrapper of the cigarette with 10 a resinous composition, and allowing the liquid portion of the coating composition to evaporate, as herein set forth.

4. A process for reducing the inflammability of a cigarette when partially consumed, comprising coating the paper portion of the cigarette with a synthetic resin composition substantially odorless and tasteless containing a fire-retardant 15 therein, as herein set forth.

5. A process for reducing the inflammability of a cigarette when one-quarter to three-quarters consumed, comprising coating the paper portion of the cigarette at one or more places with a phenol-aldehyde composition containing an inflammability-reducing material therein, and allowing the liquid portion of the coating composition to evaporate, as herein set forth. 20

6. A process for producing a cigarette a portion of the wrapper of which is difficultly burnable, comprising coating the paper portion of 30 the cigarette in a plurality of applications with an inflammable solution of non-cellulosic composition substantially odorless and tasteless containing a fire-retardant therein, and allowing the liquid portion of the coating composition to 35 evaporate, as herein set forth.

7. A process for producing a cigarette a portion of the wrapper of which is of diminished inflammability, comprising coating the paper portion of the cigarette for the width desired 40 with an inflammable solution of non-cellulosic composition containing an inflammability-reducing material therein, as herein set forth.

8. A process for reducing fire hazard in the consumption of cigarettes, comprising coating 45 the paper wrapper with a resinous composition, and allowing the liquid portion of the coating composition to evaporate, as herein set forth.

9. A process for reducing the inflammability of that portion of a cigarette which normally is 50 discarded, comprising impregnating the paper wrapper with a synthetic resin composition containing a fire-retardant therein, as herein set forth.

10. A process for reducing the inflammability of a cigarette at a pre-determined place, comprising coating the wrapper of the cigarette with a phenol-aldehyde composition substantially odorless and tasteless containing an inflammability-reducing material therein, and allowing 60 the liquid portion of the coating composition to evaporate, as herein set forth.

11. A process for reducing the inflammability of a cigarette when one-quarter to three-quarters consumed, comprising coating the paper portion 65 of the cigarette at one or more places with a non-cellulosic composition containing an inflammable liquid with a fire-retardant therein, and allowing the liquid portion of the coating composition to evaporate, as herein set forth.

12. A process for producing a cigarette a portion of the wrapper of which is difficultly burnable, comprising coating the paper portion of the cigarette in a plurality of applications with a resinous composition substantially odorless and 75

- tasteless, and allowing the liquid portion of the coating composition to evaporate, as herein set forth.
13. A process for producing a cigarette a portion of the wrapper of which is of diminished inflammability, comprising coating the paper portion of the cigarette for the width desired with a synthetic resin composition containing a fire-retardant therein, as herein set forth.
14. A process for reducing fire hazard in the consumption of cigarettes, comprising coating the paper wrapper with a phenolaldehyde composition containing an inflammability-reducing material therein, and allowing the liquid por-
- tion of the coating composition to evaporate, as herein set forth.
15. A process for reducing fire hazard in the consumption of cigarettes comprising coating the paper portion of a cigarette for a portion of its length with an inflammability-reducing composition in an inflammable liquid comprising a phenol-aldehyde in solution, and evaporating the volatile portion therefrom, as herein described.
16. As a new article, a cigarette the wrapper of which is coated for a portion of its length with a non-cellulosic fire-retarding composition dissolved in an inflammable solvent.
